UNITED STATES PATENT OFFICE.

ALEXANDER K. SUTHERLAND, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

KNIFE-BLADE SWITCH.

1,216,513.

Specification of Letters Patent. Patented Feb. 20, 1917.

Application filed November 26, 1915. Serial No. 63,376.

To all whom it may concern:

Be it known that I, ALEXANDER K. SUTHERLAND, a citizen of the United States, residing at Plainville, county of Hartford, State of Connecticut, have invented an Improvement in Knife-Blade Switches, of which the following is a specification.

This invention relates to knife blade switches and has for its object to provide locking means which will retain the blade or blades in any predetermined position or positions, my novel locking means being especially useful in connection with double-throw switches having contact jaws both above and below the plane of the pivot, as it obviates the danger of the blades becoming disengaged from a pair of higher jaws and dropping down into contact with a pair of lower jaws in case of jarring, or loosening of the spring washers should they be used. It has been the common practice in this class of switches to set up the spring washers with considerable pressure in order to retain the blade in an intermediate position when the circuits were open, or to prevent the blade from dropping out of engagement with one pair of contact jaws and into engagement with a lower pair of contact jaws, as in switches used for reversing the circuit or for changing from local to city circuit, or from alternating to direct current and vice versa. This tightening up of spring washers has been found seriously objectionable for the reason that when the blade was gripped tightly enough by the ears to retain it in any required position, the metal would "cut." My present invention wholly does away with this difficulty.

With these and other objects in view, I have devised the novel blade-locking device, which I will now describe, referring to the accompanying drawing forming a part of this specification, and using reference characters to indicate the several parts.

Figure 1 is a side elevation of a double-pole double-throw switch with my novel locking means applied thereto;

Fig. 2 a plan view corresponding therewith;

Fig. 3 a detail elevation on an enlarged scale;

Fig. 4 a plan view corresponding therewith;

Fig. 5 a perspective view on the scale of

Figs. 1 and 2 showing the invention applied to a multi-circuit switch having pairs of contact jaws of different heights, and

Fig. 6 is a detail elevation on the scale of Fig. 3, showing a variant form of the invention.

10 denotes a base, of insulating material, 11 pairs of contact jaws secured thereto, 12 holding pieces, 13 blades, 14 an insulating cross piece and 15 a handle which in double-pole switches is secured to the cross piece and in single-pole switches by a suitable insulating connection, to the blade. The contact jaws and the holding pieces are rigidly secured to the base in any ordinary or preferred manner. The holding pieces are 70 provided with ears 16 between which the inner ends of the blades are secured by pivot bolts 17. The pivot bolts may or may not be provided with spring washers 18, adapted to be set up against one of the ears by a 75 nut 19. It should be understood that the use or non-use of spring washers is wholly immaterial so far as the present invention is concerned.

My present invention consists in providing the blades and the holding pieces with interengaging means which lock the blades at required positions. For example, I provide the blades with pins 20 and provide upon the holding pieces spring keepers 21 with which the pins are adapted to engage. The keepers are plates of spring metal each having a hole through which the pivot bolt passes and at its inner end a lug 22 adapted to be turned into a hole 23 in the holding piece to lock the keeper against movement with the blade. Each keeper is provided on its inner face, at the outer end, with a groove 24 which is adapted to receive the pin, and at its edges with inclines 25, which are adapted to be engaged by the pin, a pin, when it engages an incline, riding up the incline and springing the keeper backward until the pin engages the groove, which locks the blade yieldingly in place. 100 The tension of the keeper is sufficient to retain the blade in position against jarring or any of the conditions of use, but yields when a moderate amount of power is applied to the handle.

In Figs. 1 to 4 inclusive, the keeper and pin are so arranged as to lock the blade in its intermediate or upright position.

In Fig. 5, I have shown the invention as applied to a type of switch having a plurality of pairs of contact jaws of different heights so that when the blade is swung downward it will engage first one pair of jaws, then another, and then another. The keeper in this form is made sector-shaped, and is provided with a plurality of radial grooves, one being adapted to lock the blade 10 in its upright position, and the others to lock it in successive positions as it comes into engagement with successive pairs of contact jaws. The operation is the same as before, the only difference being duplication 15 of pairs of contact jaws and corresponding locking grooves in the keeper.

In Fig. 6, I have illustrated a variant form adapted for use with two pairs of contact jaws. In this form the keeper, instead 20 of being set in alinement with the holding piece, is set obliquely thereto and the blade, instead of having one pin located centrally, has one near each edge. The engagement of the upper pin (as seen in Fig. 6) with 25 the keeper, will lock the blade in engagement with the first pair of contact jaws and the engagement of the other pin with the keeper will lock the blade in its upright

position. No locking means is required in connection with the last pair of locking jaws 30 in a series, as it makes no difference how far the blade passes in between the jaws.

Having thus described my invention, I claim:—

1. In a switch of the character described, 35 a holding piece, a blade pivoted to the holding piece and provided with a pin, and a spring keeper secured to the holding piece and having at its outer end a groove adapted to receive and yieldingly engage the pin 40 and at its edges inclines against which the pin acts to spring the keeper backward until the pin reaches said groove.

2. In a knife blade switch, a holding piece having a hole, a blade pivoted to the 45 holding piece and provided with a pin, and a keeper removably secured to the holding piece and having at its inner end a lug engaging the hole, at its outer end a groove adapted to receive the pin and at its edges 50 inclines adapted to be engaged by the pin to spring the keeper backward until the pin engages the groove.

In testimony whereof I affix my signature.

ALEXANDER K. SUTHERLAND.
